REGULATOR VALVE APPARATUS FOR
LOCOMOTIVES AND LIKE ENGINESFrederick Arthur Boyes, Wembley, England, as-
signor to American Throttle Company, Inc.,
New York, N. Y.Application April 7, 1934, Serial No. 719,467
In Great Britain April 11, 1933

5 Claims. (Cl. 137—144)

This invention relates to regulator valve apparatus for locomotives and like engines of the kind in which admission of steam to, and the shutting off of steam from, the engine valve chests is effected by a plurality of valves of the lift or poppet type, a pilot valve being provided by the opening of which such lift valves are placed in approximate balance as to steam pressures acting on them before they are opened.

Whilst more particularly intended for use on a locomotive equipped with steam superheaters, and to be disposed between the superheater and the engine valve chests, the regulator apparatus according to this invention is not restricted to such use or disposition.

In regulator valve apparatus of the kind above referred to as heretofore constructed, the lift valves are opened in series as required to increase the steam supply to the engine and in practice it may happen at times that to obtain the appropriate port opening for flow of steam for the desired running condition of the locomotive one of the valves will be only very slightly opened or "cracked". In such a position of a valve there is a liability of the valve and valve seat being scored due to the passage of high velocity steam between the closely adjacent joint surfaces of these parts. Also when a locomotive is running the pulsation of the column of steam flowing to the engine valve chests, due to the repeated opening and cut off of the distributing valves is liable to set up fluttering of the lift valves, and should one of such valves be only very slightly opened it may chatter or hammer on its seat.

The advantages of lift or poppet valves as regards the function of shutting off steam from the engine are well known and as regards regulating the quantity of steam supplied to the engine during running the advantages of slide valves also are known.

It is the general object of the present invention to provide an improved regulator valve apparatus which shall combine the advantages of lift valves for shutting off steam and of slide valves for the quantitative regulation of the steam and which at the same time shall be such that the disadvantages above referred to will be eliminated.

It is another object of the present invention to provide a regulator valve apparatus of the type comprising a plurality of relatively small lift valves for shutting off steam to the engine in which before steam for propulsion purposes can be supplied to the engine all of the lift valves will be lifted a considerable distance from their seats so that a large port opening obtains at each lift

valve which will be maintained or increased during the running of the engine, thereby eliminating the liability of scoring of any of the valves or seats due to the passage of high velocity steam between closely adjacent valve and valve seat surfaces.

A further object of the invention is to provide a simple form of regulator valve apparatus having lift valves for shutting off the steam to the engine and slide valves for quantitative regulation of the steam during running in which the lift valves shall be efficiently balanced without the employment of balancing pistons, the valve apparatus being such that it may be used with high steam pressures without rendering it difficult to operate.

A valve apparatus according to this invention and employing a plurality of lift valves for shutting off steam from the engine may be so constructed as to render it possible to grind in such valves without dismantling the rigging through which the valves are actuated.

The construction and arrangements according to the present invention are such that existing multiple valve regulator housings and the valves themselves may be altered so as to constitute valve apparatus according to the present invention in a simple and inexpensive manner. Further the valve apparatus according to the present invention is such that the pilot valve may be used to supply steam to the engine valve chests while the engine is drifting.

Regulator valve apparatus according to the invention has other advantages over existing multiple valve regulators, amongst the advantages being that there is less risk when a valve has been lifted to a small extent from its seat of vortex action occurring which would render increased force necessary to effect a larger opening of the valve. Another advantage of the construction according to the present invention is that excessive back pressure on the valves due to the release of high compression in the engine cylinders will be damped down, or its effect on the valve reduced, a further advantage being that, as compared with existing multiple valve regulators, the intermediate or delivery chamber of the valve housing may be more shallow and also that there is less liability of water of condensation collecting in the balancing chamber. Further the construction may be such that there will be a very small and gradually increasing opening for steam to the engine, the arrangement being such that should insufficient steam be supplied by a drifting valve a small quantity may be supplied by the register valve apparatus

without setting up scoring of the valves and seats as is liable to happen where a lift valve is only open very slightly or "cracked".

- Broadly stated, the invention consists in regulator valve apparatus for locomotive or like engines of the kind comprising a chambered valve housing, a plurality of relatively small main valves of the lift or poppet type for shutting off steam from the engine and disposed in said housing, a pilot valve adapted when opened to supply steam for placing the said lift valves in approximate balance as to steam pressures acting on them, and means for actuating the valves to open them in predetermined order, wherein there is operatively secured to each main lift valve a slide valve for effecting quantitative regulation of steam supplied to the engine, the main lift valves operating only as stop valves, and the several valves and the means for actuating them being such that all the main lift valves will be lifted from their seats to a considerable extent before any one of the slide valves reaches a position in which it will uncover ports leading to the engine valve chests and permit passage of steam thereto.

The slide valves of the regulator valve apparatus according to this invention are constituted by hollow open-ended cylinders having rigid connection with the main lift valves and work in cylindrical guides or ducts having ports in their walls which are controlled by the slide valves.

In the accompanying drawings,—

Fig. 1 is a sectional elevation of a multiple valve regulator valve apparatus according to one embodiment of the invention.

Fig. 2 is a cross-section on the line X—X, Fig. 1, through one of the slide valves and the cylindrical guide or duct in which it works, and

Fig. 3 is a view similar to Fig. 1, but showing the valves in their fully operated positions.

Referring to the drawings, the valve housing therein shown comprises three superposed chambers, the upper chamber 1 being the supply chamber, the lower chamber 2 a balancing chamber, and the intermediate chamber 3 being the delivery chamber to which the pipe or pipes (not shown) leading to the engine valve chests are connected.

The lift valves 4, 5, 6, 7, seat, as usual, in multi-valve regulator apparatus of the type to which the invention relates at apertures in the wall or partition 8 between the supply chamber 1 and the delivery chamber 3 of the housing, appropriate valve seats being provided at such apertures. The pilot valve, which is also of the lift valve type, seats on a valve seat provided at an aperture in an extension 8a of the partition 8, and when opened admits steam, as usual, from the supply chamber 1 to the balancing chamber 2. Preferably, as shown in the drawings, the pilot valve 9 has another valve 10 associated with it, in order that it may be used to supply steam to the engine valve chests while the engine is drifting, a portion 11 of the balancing chamber 2 being divided off by a wall 12 to provide a drifting steam chamber to which is connected the drifting steam pipe 13.

In a regulator valve apparatus according to this invention, instead of the lift valves 4, 5, 6, 7 being equipped with balancing pistons as in the multiple valve regulator apparatus now in use, such valves are balanced by steam admitted directly to the under sides of the valves as is the case with all the valves (with the exception of that first opened) in the multiple valve regulator

apparatus shown and described in Reissued Patent No. 16,285, granted to Ray M. Brown. Instead of the valve stems being equipped with balancing pistons, such valve stems carry hollow cylindrical members or sleeves 14, 15, 16, 17 and tubular guides or ducts 18 extend from the partition 8 between the supply and delivery chambers of the housing to the partition 19 between the delivery and balancing chambers, the upper ends of these tubular guides or ducts constituting the seats for the lift valves 4 . . . 7. The cylindrical sleeves 14 . . . 17 or sleeve valves, as they may be termed, are shown in the drawings as being carried by radial arms or wings projecting from the spindles of the main lift valves.

Preferably, three equi-distantly spaced arms 20 are provided on each spindle and such arms or wings may have portions cut away intermediate their ends as indicated in dotted lines at 21, Fig. 1, thus constituting upper and lower sets of arms. As shown at an appropriate distance below their upper edges the arms or wings 20 are rabbeted to form shoulders, against which the upper edges of the sleeve valves 14 . . . 17 abut, the sleeve valves being welded to the arms at their lower edges. Any other convenient manner of securing the sleeve valves to the main valve spindles may be employed, but it will be understood that the construction and arrangement must be such that a free passage obtains between the valve and the valve spindle in each case.

Appropriately positioned in the tubular guides or ducts 18 are ports 22 leading through the walls of the ducts into the delivery chamber of the housing.

In the closed position of the lift valves 4 . . . 7, the sleeve valves 14 . . . 17 close the ports 22, and the sleeve valves are of such a length that a substantial lift must be given to the lift valves before the sleeves begin to uncover the ports 22 leading to the delivery chamber of the valve housing.

The pilot valve 9 and the shut-off and regulating valves 4 . . . 7 and 14 . . . 17 are actuated by a rockshaft 23 mounted in suitable bearings 45 and extending along the balancing chamber of the housing, the rockshaft having fingers or cams 24 extending radially from it and adapted to actuate the valves by engaging heads or shoulders on the valve stems in the now well-known manner, and it is not thought necessary to give further description of this actuating means herein, except to point out that the fingers or cams 24 and the arc of movement of the rockshaft 23 are such that after the pilot valve 9 has been opened the main shut-off valves 4 . . . 7 will be raised from their seats to a substantial extent before any one of the sleeve valves uncovers its associated ports 22, and that, after such substantial opening of the lift valves has taken place, continued movement of the rockshaft 23 will cause the sleeve valves 14 . . . 17 to open their associated ports 22 in the predetermined order. The regulation of the quantity of steam supplied to the engine will be effected by manipulating the regulator lever to effect appropriate movements of the sleeve valves 14 . . . 17.

With the parts constructed as shown in the drawings the initial portion of the movement of the rockshaft 23 will open the pilot valve, and steam will flow past such valve into the chamber 11 and past the valve 10 into the balancing chamber 2, from whence it will flow up through the sleeve valves 14 . . . 17 to the under sides of the main lift or stop valves 4 . . . 7, placing these 75

valves approximately in balance as regards steam pressure acting on their opposite sides. Continued movement of the rockshaft then raises the lift valves from their seats in the order determined by the cams 24. As shown, the valve 4 will be the first to be lifted, and this will be followed by the valve 6, the valves 5 and 7 being opened thereafter in the order named. As already pointed out, the valves 4 . . . 7 will be raised to a substantial extent above their seats before the sleeve valve 14 will open its associated ports. The sleeve valves will open in the same order as the lift valves. When a sleeve valve is opened steam from the supply chamber 1 will flow between the lift valve and its seat, through the sleeve valve, and around its lower edge into and through the associated ports 22. At the same time during the running of the engine the pilot valve 9 will be fully open, and a substantial flow of steam past this valve will obtain, such steam flowing into the balancing chamber, and thence through such ports 22 as may be uncovered by one or more of the slide valves 14 . . . 17, this steam flowing into the delivery chamber in addition to the steam which flows directly from the supply chamber past the main stop valves 4 . . . 7.

Assuming that some only of the sleeve valves to be in position opening ports leading to the delivery chamber it will be understood that the lift valves associated with the remaining one or more of the sleeve valves will be opened and thus steam from the supply chamber can flow past such lift valve or valves into the balancing chamber and with the steam passing the pilot valve can flow from the balancing chamber into the delivery chamber by way of ports 22 uncovered by such slide valve or valves as is or are open. Thus during the running of the engine there will be a flow of steam through the ports 22 leading into the delivery chamber from two directions, that is both from the supply chamber of the valve housing and from the balancing chamber and this factor will assist in preventing fluttering or chattering of the lift valves, and also reduce the liability of water or condensation accumulating in the balancing chamber.

In order to obtain a gradual opening of the ports by the sleeve valves the lower edges of such ports may be inclined to the horizontal plane in which the seats for the lift valves 4 . . . 7 lie. Conveniently the lower edges of the ports 22 are inclined downwardly to their centres as clearly shown in Fig. 3 and in connection with the sleeve valve 15 in Fig. 1.

Variations in some of the constructional details described herein may be made without departing from the invention. For example, the sleeve valves might be formed integrally with the stems of the lift valves, if desired, or a sleeve valve might be carried by arms from a central tubular member adapted to be slid into position on the lift valve stem, in which case the heads engaged by the cams 24 on the rockshaft 23 would be separately formed from the stem and appropriately secured thereto, the upper head serving to hold the sleeve valve in its appropriate relation to the lift valve.

What I claim is:—

1. Regulator valve apparatus for locomotive or like engines of the kind comprising a chambered valve housing, a plurality of relatively small main valves of the lift type for shutting off steam from the engine and disposed in said housing, a pilot valve adapted when opened to supply steam for placing the said lift valves in approximate balance as to steam pressures acting on them, and means for actuating the valves to open them in predetermined order, wherein there is operatively secured to each main lift valve a slide valve for effecting quantitative regulation of steam supplied to the engine, the main lift valves operating only as stop valves, and the several valves and the means for actuating them being such that all the main lift valves will be lifted from their seats to a considerable extent before any one of the slide valves reaches a position in which it will uncover ports leading to the engine valve chests and permit passage of steam thereto.

2. In regulator valve apparatus the combination of a housing having a steam supply chamber constantly open to a source of steam, a balancing chamber, and a delivery chamber interposed between the supply and balancing chambers and connected to the engine valve chests, a plurality of cylindrical ducts connecting said supply and balancing chambers and having ports through their walls leading to the delivery chamber, a slide valve in each duct controlling the ports, the supply chamber end of each duct being shaped to form a valve seat, lift valves connected to said slide valves and adapted to engage said seats, the slide valves being hollow open-ended cylinders affording free passage for steam from the balancing chamber to act on the lift valves and place them approximately in balance before they are opened and, when the lift valves are opened sufficiently, affording free passage for steam from the supply chamber to the ports controlled by the slide valves, the several valves and the means for actuating them being such that all the main lift valves will be lifted from their seats to a considerable extent before any one of the slide valves reaches a position in which it will uncover ports leading to the delivery chamber.

3. Regulator valve apparatus as claimed in claim 2, wherein the slide valves are formed separately from the main lift valves and are connected to the stem of such valves by arms or wings.

4. Regulator valve apparatus as claimed in claim 2, wherein the ports in the cylindrical ducts controlled by slide valves have their edges remote from the lift valve seats inclined to the plane in which such seats lie, for the purpose set forth.

5. Regulator valve apparatus as claimed in claim 2, wherein the cylindrical ducts connecting the supply and balancing chambers are constituted by sleeves formed separately from the main body of the valve housing, and extend from the partition between the supply and delivery chambers to the partition between the balancing and delivery chambers, each said sleeve being at one end formed to provide the seat for the associated lift valve, and the sleeves being fitted in aligned apertures in the partitions.

FREDERICK ARTHUR BOYES.
